UNITED STATES PATENT OFFICE

JOHN F. LINDBERG, OF CHICAGO, ILLINOIS, ASSIGNOR, BY MESNE ASSIGNMENTS,
TO THE YODER PENCIL COMPANY, OF CLEVELAND, OHIO, A CORPORATION OF OHIO

PENCIL

Application filed November 25, 1921. Serial No. 517,537.

My invention relates to pencils of the class which employ mechanism for feeding the leads or other marking rods thereof, and resides in providing improved means whereby the marking rods are preferably fed automatically to maintain them in writing adjustment, the device of my invention rendering it unnecessary to effect any manual adjustment of the marking rods to compensate for the wear thereupon, though the invention is not to be limited to automatic action.

In the preferred embodiment of my invention there is employed a casing, a marking rod, and a hollow guide within and movable longitudinally of the casing and provided for and enclosing the marking rod that projects through the outer end of its guide, said guide projecting at this end thereof through an opening provided in said casing at the writing end of the pencil.

There is also provided a follower rod within the casing and in abutting engagement with the inner end of the marking rod, a clutch disposed within and mounted upon the casing and in gripping relation to the follower rod and engaging said guide, a spring pressing upon the clutch in a direction to grip the follower rod and to place the guide in a fully projected position, said guide, when pushed inwardly, serving to release said clutch from holding engagement with the follower rod, and a spring pressing outwardly upon said follower rod and serving to move it and the marking rod outwardly when said clutch is released.

Any suitable means may be employed for preventing the marking rod from falling out when the follower rod is clutched and when the guide is projected to its outermost position. This means preferably resides in a spring element upon the guide and projecting at one part through a lateral opening that is provided in the guide into holding engagement with the marking rod, this part of said spring element and the casing having complementary portions that are in wedging engagement on outward movement of the guide to engage said part of the spring element with the marking rod, the spring element being

constrained to release the marking rod on inward movement of the guide.

I will explain my invention more fully by reference to the accompanying drawing showing the preferred embodiment thereof and in which Fig. 1 is a longitudinal sectional view of a pencil constructed in accordance with the invention; Fig. 2 is an enlarged sectional view of the writing end of the pencil on a larger scale than that employed in Fig. 1; Fig. 3 is a sectional view on line 3—3 of Fig. 1; Fig. 4 is a sectional view on line 4—4 of Fig. 1; Fig. 5 is a perspective view of the guide for the marking rod; and Fig. 6 is a perspective view showing a housing for the feeding spring and the inner end of the follower rod, this housing being in fixed relation with the casing and serving as a mounting for the clutch.

Like parts are indicated by similar characters of reference throughout the different figures.

The pencil structure includes a tubular casing 1 that is tapered at the writing end of the pencil to constrict its bore so that this casing may there have sliding fit with the guide 2 that is to project to a limited extent beyond the casing. This guide is preferably tubular and is formed with a collar 3 at its inner end to co-operate with the constricted portion of the casing at the writing end of the pencil in directing the guide in its movements longitudinally of the casing. This guide encloses the lead or other marking rod 4 that projects through the outer end of the guide a sufficient extent to enable the marking rod to be used in writing.

A follower rod 5 is provided within the casing and enters the guide 2 to be in abutting engagement with the inner end of the marking rod. This follower rod is guided in its movement by the marking rod guide 2 and also by being in sliding engagement with the plug 6 at the lower end of the tube 7 which is in fixed relation with and within the casing 1. The rod is further guided in its movements longitudinally of the casing by means of the head 8 thereon that is in sliding fit with and within the tube 7. A feeding spring 9 is housed by the tube 7 and

is interposed between and engages an abutment 10, fixed upon and within the tube 7 and the head 8 upon the follower rod. This spring is under compression and when it is free to function it presses the follower rod outwardly and with it the marking rod. A ring clutch 11 surrounds the follower rod and has a tongue 12 that passes through an opening 13 in the tube extension 14 of the plug 6 whereby the clutch tongue 12 is given support.

A coiled spring 15 surrounds the follower rod and is disposed within the tubular continuation 14 of the plug 6 between the plug 16 and the clutch. This spring serves to place the clutch in a position in which it grips the follower rod to prevent the spring 9 from functioning. This clutch also engages the inner end of the tubular guide 2 so that the spring, in addition to performing its clutch applying function, also serves to place the guide 2 in its outermost position, the extent to which this guide is projected being limited by the position of the clutch when gripping the follower rod.

A spring element is preferably employed for holding the marking rod and the guide when the guide is in its outermost position. This spring element desirably includes a leaf spring 16 that is anchored at its inner end upon the guide and is formed with a gripping nose 17 at its outer end which projects through a lateral opening 18 that is provided in the guide. This nose has wedging engagement with the tapering portion of the casing 1, the nose preferably having its outer face sloping toward the writing end of the pencil as indicated most clearly in Fig. 1. When the spring 15 places the guide in its outermost position the nose 17 of the spring element will be forced inwardly by the tapering end of the casing 1 to engage the marking rod and prevent it from dropping out.

When the pencil is being used the writing pressure exerted thereby is not only effective in causing the proper application of the marking rod upon the paper but is also effective to press the guide 2 upwardly when the marking rod is sufficiently worn to bring the outer end of the guide into contact with the paper. The inward movement of the guide which is thus effected is in opposition to the clutch spring 15 and in this inward movement the guide moves the clutch 11 to a releasing position in opposition to said spring and the guide in this inward movement carries the spring element 16 with it to release the clamping nose 17 from engagement with the marking rod to permit this marking rod to be forwardly fed as will presently appear, it being understood that the spring 16 is constrained to place this nose 17 in releasing position when this spring, and the guide 2 carrying it, are moved inwardly. When the clutch is thus released

the spring 9 is permitted to press the follower rod outwardly until the marking rod has been adjusted to its proper writing position at which time the guide 2 is so far released from engagement with the paper that the clutch spring will again be permitted to act to place the clutch in a position to hold the follower rod and prevent the operation of the feeding spring 9. When the clutch is being placed in this position it will move the guide 2 to its outermost position and the guide, in completing this movement, will effect the application of the clamping nose 17 to the marking rod to hold the rod from falling out.

The adjusting movements that automatically follow the use of the pencil are slight and frequent so that the marking rod is always projected a sufficient distance beyond the pencil casing to enable such rod properly to function.

When the marking rod has been consumed it may readily be replaced by a new one that is merely inserted through the writing end of the casing and into the guide 2 against the force of the spring 9, the clutch spring 15 then yielding.

The tube 7 may be continued upwardly to constitute a holding socket for an eraser 18, that is enclosed by a removable cap 19 slipped over the top end of said tube. A magazine 20 for spare pencil leads may be held within the bore of spring 9, in which event the eraser is removable to afford access to the magazine.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. In a pencil, the combination with a casing; of a marking rod; a hollow guide within and movable longitudinally of the casing and provided for and enclosing the marking rod that projects through the outer end of its guide, said guide projecting at this end thereof through an opening provided in said casing at the writing end of the pencil to be engageable with the object written upon; a spring element upon said guide and projecting at one part through a lateral opening that is provided in the guide into holding engagement with the marking rod, this part of said spring element and the casing having complementary portions that are in wedging engagement on outward movement of the guide to engage said part of the spring element with the marking rod, the spring element being constrained to release the marking rod on inward movement of the guide; a follower rod within the casing and in abutting engagement with the inner end of the

marking rod; a clutch disposed within and mounted upon the casing and in gripping relation to the follower rod and engaging said guide; a spring pressing upon the clutch in a direction to grip the follower rod and to place the guide in a fully projected position, said guide, when pushed inwardly, serving to release said clutch from holding engagement with the follower rod; and a spring pressing outwardly upon said follower rod and serving to move it and the marking rod outwardly when said clutch is released.

2. In a pencil, the combination with a casing; of a marking rod; a hollow guide within and movable longitudinally of the casing and provided for and enclosing the marking rod that projects through the outer end of its guide, said guide projecting at this end thereof through an opening provided in said casing at the writing end of the pencil to be engageable with the object written upon; a follower rod within the casing and in abutting engagement with the inner end of the marking rod; a clutch disposed within and mounted upon the casing and in gripping relation to the follower rod and engaging said guide; a spring pressing upon the clutch in a direction to grip the follower rod and to place the guide in a fully projected position, said guide, when pushed inwardly, serving to release said clutch from holding engagement with the follower rod; and a spring pressing outwardly upon said follower rod and serving to move it and the marking rod outwardly when said clutch is released.

3. In a pencil, the combination with a casing; of a marking rod; a hollow guide within and movable longitudinally of the casing and provided for and enclosing the marking rod that projects through the outer end of its guide, said guide projecting at this end thereof through an opening provided in said casing at the writing end of the pencil to be engageable with the object written upon; a follower rod within the casing and in abutting engagement with the inner end of the marking rod; a clutch disposed within and mounted upon the casing and in gripping relation to the follower rod and engaging said guide; a spring pressing upon the clutch in a direction to grip the follower rod and to place the guide in a fully projected position, said guide, when pushed inwardly, serving to release said clutch from holding engagement with the follower rod; a spring pressing outwardly upon said follower rod and serving to move it and the marking rod outwardly when said clutch is released; and means for holding the marking rod when its guide is in outermost position.

4. In a pencil, the combination with a casing; of a marking rod; a guide within and movable longitudinally of the casing and provided for the marking rod that projects beyond the outer end of its guide, said guide

projecting at this end thereof through an opening provided in said casing at the writing end of the pencil to be engageable with the object written upon; a follower rod within the casing and in abutting engagement with the inner end of the marking rod; a clutch disposed within and mounted upon the casing and in gripping relation to the follower rod and engaging said guide; a spring pressing upon the clutch in a direction to grip the follower rod and to place the guide in a fully projected position, said guide, when pushed inwardly, serving to release said clutch from holding engagement with the follower rod; and a spring pressing outwardly upon said follower rod and serving to move it and the marking rod outwardly when said clutch is released.

5. In a pencil, the combination with a casing; of a marking rod; a guide within and movable longitudinally of the casing and provided for the marking rod that projects beyond the outer end of its guide, said guide projecting at this end thereof through an opening provided in said casing at the writing end of the pencil to be engageable with the object written upon; a follower rod within the casing and in abutting engagement with the inner end of the marking rod; a clutch disposed within and mounted upon the casing and in gripping relation to the follower rod and engaging the guide; a spring pressing upon the clutch in a direction to grip the follower rod and to place the guide in a fully projected position, said guide, when pushed inwardly, serving to release said clutch from holding engagement with the follower rod; a spring pressing outwardly upon said follower rod and serving to move it and the marking rod outwardly when said clutch is released; and means for holding the marking rod when its guide is in outermost position.

6. In a pencil, the combination with a casing; of a marking rod; a guide within and movable longitudinally of the casing and provided for the marking rod that projects beyond the outer end of its guide, said guide projecting at this end thereof through an opening provided in said casing at the writing end of the pencil to be engageable with the object written upon; a spring element upon said guide and projecting at one part into holding engagement with the marking rod, this part of said spring element and the casing having complementary portions that are in wedging engagement on outward movement of the guide to engage said part of the spring element with the marking rod, the spring element being constrained to release the marking rod on inward movement of the guide; a follower rod within the casing and in abutting engagement with the inner end of the marking rod; a clutch disposed within and mounted upon the casing

and in gripping relation to the follower rod and engaging said guide; a spring pressing upon the clutch in a direction to grip the follower rod and to place the guide in a fully projected position, said guide, when pushed inwardly, serving to release said clutch from holding engagement with the follower rod; and a spring pressing outwardly upon said follower rod and serving to move it and the marking rod outwardly when said clutch is released.

7. In a pencil, the combination with the casing thereof having an opening therein at the writing end of the pencil; of a marking rod projecting through said opening; and mechanism for feeding the marking rod and including an operating element projecting through the casing alongside of the marking rod and actuatable, to feed the marking rod, by contact with the object being written upon, said feeding mechanism being operable to feed the rod while the projecting element contacts with said object.

8. In a pencil, the combination of a body, a pair of concentrically arranged relatively movable elements normally projecting beyond one end of said body, the inner element comprising a section of lead and the outer element being slidably mounted in said body, a pair of springs each acting on one of said elements to move it outwardly, and a pair of devices correlated to limit the outward movements of said elements but arranged to release said inner element when said outer element moves inwardly relative thereto.

9. In a pencil, the combination of a body, a pair of concentrically arranged relatively movable elements normally projecting beyond one end of said body, the inner element comprising a section of lead and the outer element being slidably mounted in said body, a pair of springs each acting on one of said elements to move it outwardly, and means for limiting the outward movement of said elements but arranged to release the inner element when said outer element moves inwardly relative thereto.

10. In a pencil, the combination of a hollow body, a lead projecting from one end thereof, a feed member engaging said lead, a coiled spring acting on said feed member to move it longitudinally of said body, means for controlling the movement of said feed member, and a tubular member mounted in the upper end of said body and disposed within said coiled spring for holding extra leads.

11. In a lead pencil, the combination of a holder, a lead carrying tube slidably mounted in said holder with one end projecting beyond the writing end thereof, a propelling device fitting in the inner end of said tube and engaging the inner end of the lead, means normally acting on said device to propel the lead through the tube, and clutch means carried by said tube and arranged to

engage said propelling device to lock it against outward movement, but releasable therefrom upon movement of said tube inwardly due to its engagement with a surface under the influence of normal writing pressure.

In witness whereof, I hereunto subscribe my name this 23rd day of November, A. D., 1921.
